ROTARY AND VERTICALLY MOVABLE DRUM
FOR CAN SEALING MACHINESRobert George Bach, Griffithstown, England, and
John Roy Paton, Lisvane, WalesApplication September 21, 1944, Serial No. 555,122
In Great Britain September 30, 1943

6 Claims. (Cl. 226—82.4)

1

The invention relates to improvements in machines for seaming cans.

It is an object of the invention to provide an automatically effective apparatus for hermetically applying lids to cans and to perform this operation in rapid sequence successively on cans.

Another object of the invention is to control the seaming operation by rendering it dependent upon the approach of a can to position for sealing.

It is, furthermore, an object of the invention to assure the proper positioning of the can to be sealed with respect to the cover or lid to be applied thereto and to locate for this purpose the carrier of the can in an accurately determined position when the can supported by the carrier reaches the position for operation.

With these and numerous other objects in view, an embodiment of the invention has been illustrated in the accompanying drawing to which reference is made in the following specification.

In the drawing:

Fig. 1 is a side elevation of a seam applying machine to which the filled cans are successively conveyed.

Fig. 2 is a detail side elevation illustrating the means for accurately determining the position of the carrier for the seaming operation;

Fig. 3 is a detail and side elevation showing the control of the carrier for moving to and withdrawing from the seaming position.

Fig. 4 shows partly in elevation and partly in section the seaming head and seaming rollers.

The vacuum double seamer apparatus, shown more particularly in Figs. 1 to 4, comprises a closed hollow pedestal casting 48 which acts not only as what may be termed the body structure of the machine, but also as a vacuum receiver. This air-tight foundation casting has associated therewith a seaming head mechanism 49, a vacuum pump 50, a motor 51 to operate both these latter, and the step-by-step rotated receiving member 52.

This receiving and feeding member 52 is in the form of a drum mounted on a horizontal axis 53 and having on the exterior a plurality of flat surfaces 54 with recesses 55 (for example thirteen as shown). Each of the recesses 55 is adapted to receive as it comes round to a certain stopping position, say and as shown the "10 o'clock" position, from a pivoted guide 56 and assisted by the sweeping action of the operator's hand, a loosely lidded filled can 57 in such a manner that the

2

upper lidded end projects as shown in Fig. 1 to a desired extent from its flat surface 54.

The more or less fixed end of the pivoted guide 56 forms a continuation from a conveyor leading from the inspection and lidding position for the cans, not shown. The spindle 53 of the drum 52 is supported by bracket bearings 58 which are mounted to slide vertically in a guideway 59 attached to the main frame 48 and connected by links 60 to extensions of the pivoted guide 56. 61 is a seat for an operator and 62 a foot pedal at one end of an arm of a two-armed lever the other arm 63 of which takes beneath a roller 64 in connection with the vertically sliding bracket bearings 58, to raise the drum 52 upon the depression of the pedal 62.

65 is a bracket connecting the guide 56 to the framework of the machine and this bracket also forms the foundation for the end of a rod 66 having mounted therearound a compression spring 67 the upper end of which spring takes beneath the guide 56. 68 is a hand wheel having a screwed bore mounted to work upon the screwed lower end of the rod 66 to adjust the compression of the spring 67.

The action of this part of the mechanism is such that when the pedal 62 is depressed, the drum 52 is raised to bring the can 57 which is in the uppermost position into operative engagement with the vacuum double seamer mechanism as shown in Fig. 4 and more fully described hereafter. As will be understood, the spring 67 to a large extent compensates for the weight of the drum 52 and cans carried thereby and is so adjusted that only a slight pedal effort is necessary to raise the drum but assuring that when the effort is finished, the drum drops by its own weight.

In Fig. 1 the drum 52 is shown in its lowermost position. Raising takes place in two stages and Fig. 4 shows an enlarged view partly in section of the drum 52 raised through the first stage and ready to be raised through the second stage.

As will be seen from Fig. 4, the seaming head 49 has projecting from the under side thereof a circular vertically movable valve 101 normally pressed downwards by compression springs 102. This valve has a rubber sealing gasket 103 against which the particular flat surface 54 of the drum 52 which is in position makes contact in the first stage of the upward movement of the drum.

The valve 101 has an aperture 104 with sufficient clearance to permit the can with the extended flanges of the lid and body readily to pass therethrough as shown.

Laterally, the side walls of the valve 101 fit so as to slide vertically in the interior section of the lower part of the seaming head 49 and these walls have therein two slots, namely 105 termed the atmospheric port slot and 106 termed the vacuum port slot the latter of which comes a desired vertical distance above the former.

In the chamber of the seaming head 49 there is a lower port 107 to atmosphere and an upper port 108 to the vacuum receiver or chest 48. These two ports co-operate with the ports 105 and 106 of the valve 101 so that in the lower position of the said valve the atmospheric port slot 105 thereof coincides with the port 107 to atmosphere and consequently the interior of the head 49 is in that case open to atmosphere, it being observed that in this position the vacuum port slot 106 has not yet risen high enough to communicate with the port 108 to the vacuum receiver.

In the first stage of the rising movement and as shown in the drawing (Fig. 4), the atmospheric port slot 105 is in communication with the port 107 to atmosphere and thereafter when the drum 52 is lifted through the second stage, the springs 102 are compressed, the gasket 103 seals the interior of the head 49 from the atmosphere, the port 105 ceases to communicate with the port 107, and the port 106 communicates with the port 108. Thus the interior of the head 49 is placed in communication with the vacuum chest to exhaust air from the chamber 49 and from the interior of the particular filled and loosely lidded can which is in in position.

109 is a central fixed seaming chuck the lower member 110 of which is disposed and shaped to engage by its disposition and profile the recessed portion of the lid definitely to hold this in position on its can under slight pressure. Thus held, the seaming rollers 111 operate upon the flanges to effect the double seaming to bring these flanges into the condition such for example as shown in Fig. 13 of our co-pending application Serial No. 555,123.

After the can in the raised position has been exhausted and sealed, the drum 52 is allowed to return to its lower position and this automatically causes it to be indexed on one step by the mechanism indicated in Fig. 2 which shows a fragmentary side elevation of the drum and certain co-operating parts which not only effect the indexing of the drum but also its accurate registration in the stopping position and when it is raised to co-operate with the seamer proper.

The side of the drum 52 has at equiangular spaced positions and the same radius from the centre, a number of shaped projections 69 equal in number to the flat surfaces 54 whilst the side frame casting of the machine has a flap 70 pivoted towards its lower end, working in conjunction with an inverted U-shaped abutment 71. In operation, when the drum 52 is raised (which is the full line position shown in Fig. 2) one of the shaped projections 69 enters the channel of the abutment 71 (as shown in the drawing) and this acts to register the drum and the uppermost can in the correct position. When in this position the flap 70, which is biassed, falls over to the dotted position shown in Fig. 2. As a consequence, when the drum is lowered, the uppermost projection 69 rides on the surface of the flap to assist in the rotation of the drum through a desired angle, any turning back being stopped by the pawl and ratchet 72, the amount of angular movement being limited by the next projec-

tion 69 again bringing the flap 70 to its upright position, as will be seen from Fig. 2 where one of the projections 69 (which is shown dotted and indicates the lower position of the drum) has come into this relationship with the flap 70.

When the process according to the invention is in operation, the seaming head mechanism 49 and the pump 50 will be running continuously and a suitably located and driven interrupter cam (shown in Fig. 3 and its general position indicated by 73, Fig. 1) is provided, which will only allow the drum 52 to rise and enter the unseamed loosely lidded filled can body into position, whilst the seaming rolls of the seaming head mechanism (not shown) are at their most outward and clear point of travel. In Fig. 3, 58 is one of the bracket bearings for the drum, a linked arm 74 of which having a follower 75, co-operates with a grooved cam 76 driven by a shaft from the motor 51 through worm and worm wheel mechanism 77. This cam is of such nature that the follower 75 when raised, by the upward movement of the bracket 58 stops the rise of the drum until the entry point 78 of the cam groove is attained, which is so set that this coincides with the required position of the seaming rolls. The cam serves also to hold the drum in the upper position during the seaming operation and assists by its portion 79 in effecting the lowering and indexing movements of the drum.

It will be understood that the filled can which has been exhausted and seamed, and indexed through one position on the lowering of the drum, 35 remains in its recess 55 until by continuous indexing movements of the drum it is tipped out on to a conveyor 80, Fig. 1. It passes thereon by gravity or otherwise either directly to the oven (if it is not to be lacquered) or else to the lacquering bath not shown.

The invention is not limited to the precise forms or details of construction herein described, as these may be varied to suit particular requirements.

45 What we claim and desire to secure by Letters Patent of the United States of America is:

1. In a vacuum double seamer for exhausting and seaming cans, the combination comprising a base forming a vacuum reservoir, a vacuum seaming mechanism, a vacuum pump, a multifaced drum rotatably supported by said base, each face of said drum being provided with means for receiving a filled and loosely lidded can, manually operable means for raising said drum so as to present a can on a face thereof to said seaming mechanism, a motor for driving said pump and operating said seaming mechanism, and means controlled by said motor for preventing the raising of said drum by said manually operable means until said seaming mechanism is in position to properly engage the can for the seaming operation.

2. In a vacuum double seamer for exhausting and seaming cans, the combination comprising a base forming a vacuum reservoir, a vacuum seaming mechanism, a vacuum pump, a multifaced drum rotatably supported by said base, each face of said drum being provided with means for receiving a filled and loosely lidded can, manually operable means for raising said drum so as to present a can on a face thereof to said seaming mechanism, means for causing said drum to rotate one step in one direction when said drum descends from its raised position to bring the can 65 on the next face of the drum in position to be

presented to the seaming mechanism, means for preventing said drum from rotating in the opposite direction, a motor for driving said pump and operating said seaming mechanism, and means controlled by said motor for preventing the raising of said drum by said manually operable means until said seaming mechanism is in position to properly engage the can for the seaming operation.

3. In a vacuum double seamer for exhausting and seaming cans, the combination comprising a base forming a vacuum reservoir, a vacuum seaming mechanism, a vacuum pump, a multifaced drum rotatably supported by said base, each face of said drum being provided with means for receiving a filled and loosely lidded can, manually operable means for raising said drum so as to present a can on a face thereof to said seaming mechanism, means for causing said drum to rotate one step in one direction when said drum descends from its raised position to bring the can on the next face of the drum in position to be presented to the seaming mechanism, means for preventing said drum from rotating in the opposite direction, a motor for driving said pump and operating said seaming mechanism, and means controlled by said motor for preventing the raising of said drum by said manually operable means until said seaming mechanism is in position to properly engage the can for the seaming operation, said last named means including a cam rotated continuously by said motor, and a cam follower associated with said drum, said cam after the completion of the seaming of the can being effective to assist in rotating said drum in said one direction during the descending movement of the drum.

4. In a vacuum double seamer for exhausting and seaming cans, the combination comprising a base forming a vacuum reservoir, a vacuum seaming mechanism on top of said base, a vacuum pump, vertically slidable bearings on said base, a multifaced drum rotatably mounted in said bearings, each face of said drum having a cavity for receiving therein a filled and loosely lidded can, manually operable means, including a foot pedal, for raising said bearings and therewith said drum to present the latter to the seaming mechanism, a motor for driving said pump and operating said seaming mechanism, and means controlled by said motor for preventing the raising of said drum by said manually operable means until said seaming mechanism is in position to properly engage the can for the seaming operation, said last named means in-

cluding a cam rotated continuously by said motor and a cam follower attached to one of said bearings, said cam controlling the raising of said drum with respect to the operation of said seaming mechanism.

5. In a vacuum double seamer as claimed in claim 1, in which said seaming mechanism includes a seaming head provided in its interior with seaming rollers for engaging the rims of the lid and can to seam them together, and including a valve fitting on said seaming head and surrounding the can on the face of the drum which presents said can to the seaming mechanism, said valve fitting in the raised position of said drum engaging sealingly the face of the drum directly below the seaming head, and means controlled by the movement of the drum into engagement with said valve fitting for bringing the interior of the seaming head into communication with said vacuum reservoir, whereby the air is exhausted from the space within which the can is seamed.

6. In a vacuum double seamer for exhausting and seaming cans as claimed in claim 1, in which said seaming mechanism includes a seaming head and a valve fitting mounted for axial sliding movement thereon, said valve fitting having an aperture for admitting a can positioned on a face of said drum, means on said valve fitting for establishing a seal around said aperture and a face of the drum, when said drum is raised, said seaming head and said valve fitting having cooperating ports normally out of registration with each other, said ports in the raised position of said drum are being moved into registration with each other owing to a sliding movement of said valve fitting caused by said drum, and thereby establishing communication of the interior of said seaming head with said vacuum reservoir so as to exhaust the atmospheric air from the can in said sealing head.

ROBERT GEORGE BACH.
